US0D1055357S

(12) **United States Design Patent** (10) Patent No.: **US D1,055,357 S**
(45) Date of Patent: ** Dec. 24, 2024

(54) **LED PANEL LIGHT**

(71) Applicant: **Wuxi Sea star lighting Co., Ltd.**,
Wuxi (CN)

(72) Inventors: **Weiwei Zhao**, Wuxi (CN); **Jiyong Liu**,
Wuxi (CN); **Xinrong Sha**, Wuxi (CN)

(73) Assignee: **Wuxi Sea star lighting Co., Ltd.**,
Wuxi (CN)

(**) Term: **15 Years**

(21) Appl. No.: **29/859,841**

(22) Filed: **Nov. 14, 2022**

(51) LOC (14) Cl. **26-05**

(52) U.S. Cl.

USPC **D26/89**

(57) **CLAIM**

The ornamental design for an LED panel light, as shown and described.

DESCRIPTION

FIG. 1 is a front perspective view of an LED panel light, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
